UNITED STATES PATENT OFFICE.

JULIUS BAER, OF NEW YORK, N. Y., ASSIGNOR TO WEBBING & EDGING CORPORATION, OF NEW YORK, N. Y., A CORPORATION OF NEW YORK.

DESIGN FOR BIAS TRIMMING.

Application filed December 29, 1923. Serial No. 8,189. Term of patent 7 years.

To all whom it may concern:

Be it known that I, JULIUS BAER, a citizen of the United States, residing in New York, in the county of New York, State of New York, have invented a new, original, and ornamental Design for Bias Trimming, of which the following is a specification, reference being had to the accompanying drawing, forming part thereof.

The figure shows a piece of bias trimming showing my new design.

I claim:

The ornamental design for bias trimming, substantially as shown.

JULIUS BAER.
